UNITED STATES PATENT OFFICE

2,476,047

ICE AUGER

Clifford A. Kidder, Detroit, Mich.

Application November 23, 1945; Serial No. 630,486

3 Claims. (Cl. 255—61)

1

This invention relates to boring tools, and in particular, to ice augers for boring holes in the ice, such as for fishing purposes.

One object of this invention is to provide an ice auger, the head of which may be formed from a single blank appropriately bent to form a two-lipped cutter.

Another object is to provide a blank from which, by simple bending operations, the cutter head of an ice auger may be simply and inexpensively formed.

Another object is to provide a method of making a cutter head for an ice auger wherein an annular blank is bent by simple operations to form a two-lipped cutter which may be mounted in any suitable holder.

Another object is to provide an ice auger of simple and low cost construction which is well adapted to manufacture by mass production methods.

Another object is to provide an ice auger as set forth in the preceding objects wherein the curved and bent cutter head is braced and secured to a shaft having an offset crank-like handle for rotating the shaft.

Other objects and advantages of the invention will become apparent during the course of the following description of the accompanying drawing, wherein:

Figure 1 is a side elevation of an ice auger according to a preferred embodiment of the invention;

Figure 2 is a horizontal section along the line 2—2 in Figure 1, with the cutter head in top plan view;

Figure 3 is an enlarged side elevation of the cutter head;

Figure 4 is a side elevation of the cutter head of Figure 1 taken at right angles thereto;

Figure 5 is a central vertical section through the palm rest at the top of the ice auger shown in Figure 1; and

Figure 6 is a top plan view of the blank from which the cutter head is formed by appropriate bending operations.

Referring to the drawing in detail, Figure 1 shows the ice auger of this invention as consisting of a cutter head 10 mounted on a shaft 11 having a lower portion 12, a U-shaped offset or crank portion 13 above which is an upper shaft portion 14. The shaft 11 is preferably tubular (Figure 5) with a hollow portion 15 within the upper end of which is secured and rotatably mounted a stub shaft 16. The stub shaft 16 is provided with an annular groove 17 through

2

which passes a pin 18 secured in an axially offset hole 19 (Figure 1). This enables the shaft 16 to rotate while being retained in the top portion 14 of the shaft 11.

The upper end of the stub shaft 16 is threaded as at 20, and threaded thereon is a hand wheel 21 having a threaded bore 22 engaging the threaded portion 20 of the stub shaft 16. The hand wheel 22 serves as a palm rest for grasping, while the crank portion 13 is swung through an orbital path to rotate the shaft 11.

The lower end 23 of the lower shaft portion 12 is provided with a longitudinal slot 24 (Figure 3) for receiving the web portion 25 of the cutter head 10; it being secured therein in any suitable manner, as by welding. The web 25, which is roughly in the shape of a truncated sector of a circle with a curved upper edge 26 and a curved lower edge 27, at its opposite ends 28 is sharply bent, and there joined to approximately semi-conical cutter blades 29 with cutting edges 30 optionally provided with notches 31. The cutting edges 30 are displaced outwardly on a diameter passing through the lower shaft portion 12 so that they project outwardly beyond the remainder of the cutter head 10. At the upper corners of the ends 28, braces 32 are provided (Figure 2) extending to the upper edges of the cutter blades 29 slightly rearwardly of the cutting edges 30.

The braces 32 are preferably welded in position. The cutting edges 30 and the arcuate bottom edges 33 of the semi-conical blades 29 are preferably sharpened to provide for efficient cutting action. The method of forming the blank for the cutter head 10 includes as its first step, the stamping of an annular blank 34 out of sheet metal, preferably sheet steel. The dies for this purpose are so formed as to punch out a slightly eccentric circular hole 35 and a tapered slot 36 extending from its widest point 37 to a narrow gap 38 at the periphery 39 of the blank 34. The same dies also preferably form the notches 31 in the cutting edges 30 which form the opposite edges of the slot 36. The periphery 39 is preferably circular, having its center at the point 40, whereas the center of the hole 35 is located at the point 41.

The blank 34 is then bent in opposite directions along the bending lines 42 and 43, the wings 44 and 45 thus formed being then curved in approximately conical shape to provide the cutting blades 29, the unbent portion 46 forming the web 25 with the peripheral portion 47 thereof between the lines 42 and 43 forming the upper edge 26 of the web 25. The forming of the cutter head

50

55

10 from the blank 34 may also be done by suitable dies. The cutter head 10 is then secured in the slot 24 at the lower end of the shaft 11 by welding or other suitable means. The cutting edges 30 and 33 of the blades 29 may then be sharpened, or sharpened prior to bending the wings 44 and 45 into semi-conical form.

In the use of the invention, the ice auger is held vertically with the palm of one hand firmly grasping the hand wheel or palm rest 21, and the other hand with the fingers encircling the offset or crank portion 13 of the shaft 11, with the cutter head 10 resting upon the ice. Downward pressure is then applied upon the palm rest 21 while the crank portion 13 is swung in an orbital path in a clockwise direction. Under this action, the cutting edges 33 and 30 bite into the ice and cut a conical hole through the ice. The chips of ice dislodged during the cutting operation are forced upwardly within the semi-conical spaces between the blades 29 and the web 25, tumbling over the upper edges thereof when these spaces become filled with ice chips. When the upper edges of the blades 29 reach the level of the ice, the upper portion of the hole of course becomes cylindrical and the hole becomes entirely cylindrical when the cutter head 10 passes entirely through the ice.

While I have shown and described my invention in detail, it is to be understood that the same is to be limited only by the appended claims, for many changes may be made without departing from the spirit and scope of my invention.

What I claim is:

1. An ice auger comprising a rotatable shaft, a shaft-rotating device on said shaft and a rotary cutter head of approximately frusto-conical form on the other end of said shaft, said head having a pair of partially conical cutting blades connected to said shaft, said blades having sharp 40 lateral cutting edges and sharp approximately semi-circular bottom cutting edges.

2. An ice auger comprising a rotatable shaft, a shaft-rotating device on said shaft, and a rotary cutter head of approximately frusto-conical form on the end of said shaft remote from said rotating device, said head having a plurality of wings of partially conical form thereon, the bottom edges of said wings having sharp approximately semi-circular bottom cutting edges arranged in an approximately circular path around the axis of said shaft and also having sharp lateral cutting edges projecting laterally from said wings.

3. An ice auger comprising a rotatable shaft, a handle on said shaft for rotating said shaft, and a cutter head of approximately frusto-conical form on said shaft having a diametrical web with a pair of partially conical cutting blades each connected at one end to an end of said web and having a free end with an inclined sharp cutting edge projecting laterally outward beyond the adjacent web-connected end of the other blade, the bottom edges of said blades having sharp approximately semi-circular cutting edges arranged in an approximately circular path.

CLIFFORD A. KIDDER.
